UNITED STATES PATENT OFFICE

2,043,770

ORNAMENT

Frederick W. Oltmanns, Omaha, Nebr.

Application July 27, 1935, Serial No. 33,477

3 Claims.

(CL 41—13)

This invention relates to the decorative art and more particularly to an ornamental article of manufacture and has for an object to provide a method and means which may be easily practiced and utilized for forming simulations of flowers, ornamental "sun-bursts" and the like.

A further object of the invention is to provide a new article of manufacture which in use is adapted to refract and reflect light rays and provide scintillating variegated colors of pleasing appearance to the eye and highly attractive which may not only be used for decorative purposes in homes or the like but also may be combined with store window displays for attracting the attention of prospective purchasers to merchandise and similar commercial and decorative uses of a general utilitarian nature.

A still further object of the invention is to provide a new article of manufacture for the above stated purposes, the construction of which is simple and inexpensive and requires no particular or special machinery and which may be readily manufactured manually by hand operations or manipulations.

With the foregoing and other objects in view the invention will be more particularly described hereinafter and more particularly pointed out in the claims.

In the drawing wherein like symbols refer to like or corresponding parts throughout the several views:

Figure 1 is a longitudinal section of a device which may be employed for facilitating the manufacture of the article and showing in conjunction therewith a quantity of the material from which the new article is made.

Figure 2 is a top plan view of the device shown in Figure 1, portions of the said material being broken away.

Figure 3 is a transverse section taken on the line 3—3 of Figure 1.

Figure 4 is a view similar to Figure 3 and showing the relative position of the material after a certain later described twisting operation has been applied to a wire employed.

Figure 5 is a side view of the new article having a substantially semi-globular outline or contour.

Figure 6 is a view showing a modification of the shape of the new article shown in Figure 5.

Figure 7 is an elevation of an artificial flower and showing the new article assembled with the leaves, branches and stem thereof.

Referring more particularly to the drawing, 10 55 indicates generally an aligning-trough which

may be employed, if desired, and formed of side rails 11 for supporting a concave medially disposed sheet metal trough 12. The trough, as best shown in Fig. 2, is provided with an elongated slot 13 having oppositely disposed notches 14 formed on the side edges of the slot, said notches in effect providing an aperture of greater diameter than the width of said slot for purposes later described.

The materials from which the new article is 10 formed include a twistable wire 15 and a selected quantity of elongated "straws" 16.

The straws are tubular and formed of glassine paper and may be of any selected color, said paper and straws being translucent or semi-transparent. A characteristic of the straws is 15 that they are adapted to reflect and refract light rays.

The straws are placed in a manner whereby their ends are in alignment which may be facilitated 20 and expedited by the employment of the device shown in Figures 1 to 4, said straws being piled upon each other as shown in Figure 1.

The main body portion of the wire 15 is positioned above the straws and the ends of the 25 wire inserted through the slot 13 encircling the straws in instances where the said device is employed and when said device is not used the operator may grasp a bundle of straws between the thumb and forefinger of one hand while positioning the wire with his other hand.

The operator now twists the ends of the wire or the bundle of straws for providing a loop 17 of the wire about the bundle, the twisted wire ends being indicated at 18 in Figure 4, which also 35 provides a fastening means for purposes later described.

As the twisting operation proceeds the closed loop 17 consequently becomes smaller thereby gathering the straws into a compact bundle and 40 as the twisting operation proceeds further and said loop becomes of lesser diameter the wire binds down upon the straws intermediate their ends compressing the annular wall of each straw until said walls become flattened and gathered 45 compactly adjacent the loop.

This step of the operation causes the outer or free ends of the straws which are adjacent the end of the loop or further away from the last twist of the wire or fastening means 18 to spring 50 upwardly, as shown in Figure 4, resultant from the larger amount of pressure applied by means of the wire loop to said straws and proportional to the lesser amount of pressure applied to the straws at the lower portion of the bundle adj- 55

cent said last twist of wire, the ends of said lower positioned straws remaining comparatively in alignment and forming all of the straws into a semi-spherical configuration; whereupon the thus formed article may be removed from the device 10, the notches 14 of the latter permitting a removal therethrough of the fastening means 18 which is of substantially twice the diameter of the wire 15. The slot 13 should be of a width 10 equal to the diameter of said wire.

In order to form the new article of globular outline, as shown in Figure 6, two wires are employed, the second wire being indicated at 19 in Figure 6 and illustrated by dotted lines in Figure 1.

The new article of globular shape is formed as heretofore described except that a proportionally greater quantity of straws are employed together with two wires. The wire 15 is twisted as heretofore mentioned for producing the article of semi-globular shape; whereupon the operation is repeated except that the wire 19 is employed and similarly twisted for causing the straws at the bottom of the pile to become compressed by the wire 19 proportional to the straws at the medial portion of the bundle or pile. The ends of the straws at the bottom of the bundle are thus caused to spring towards each other. At this time if but one fastening element is desired upon the article of globular shape, the second twisted wire may be trimmed shorter by means of any suitable cutting implement or bent or folded into the medial portion of the article for cancelling the wire.

Referring to Figure 7, the new article or rosette 20 may be assembled with the stem 21 for forming a simulation of a flower or that article of commerce conventionally known as an artificial flower.

Also the new article shown in Figure 5 or Figure 6 may be used in any suitable manner and combined with any suitable decoration or its fastening device 18 may be employed for hanging the article under an electric light bulb or at any selected place where display is desired.

It will be understood that light rays which enter the ends of the straws illuminate the latter more profusely than light rays which penetrate through the sidewalls thereof whereby the new article provides lights and shadows therein of pleasing effect particularly when artificial electric light or sunlight rays are provided thereon. Said straws being of the same color or of harmonizing colors a pleasing and attractive effect to the eye is presented.

In forming an article of the present invention, particularly the semi-globular article shown in Figure 5, the upstanding straws may be of lesser

length and of a different color from the other straws for providing a closer simulation of certain flowers.

Also the new article may be combined with artificial Christmas trees for decorating the latter as well as hung upon the limbs of natural Christmas trees for ornamental purposes.

The straws are formed of a translucent paper rolled upon itself or composited sufficiently to be normally self sustaining, the number of laminations to provide a tubular straw being optional. Of course, where a large ornament is desired and formed of straws of proportionally great length the number of laminations of paper for each straw is necessarily greater for providing a fairly 15 stiff straw adapted to resist normal accidental contacts with objects while at the same time said straw is compressible transversely for disposing its ends radially with respect to a medially positioned securing means such as the wire loop. 20

I do not wish to be restricted to the size, form and proportion of the various parts and obviously changes could be made in the construction herein described without departing from the spirit of the invention, it being only necessary 25 that such changes fall within the scope of the claims.

What is claimed is:—

1. As a new article of manufacture, an ornament comprising a plurality of tubular straws, 30 means binding the straws together substantially midway between their ends, said means compacting the medial portions of the straws to thereby dispose the straws in radial position about a common center.

2. The process of making ornamental decorations consisting in disposing a plurality of elongated tubular translucent straws longitudinally side by side providing a bundle, placing an elongated flexible element about the bundle between 40 the ends of the straws, twisting the ends of said element together for forming a loop encircling the bundle, and further twisting the ends of said element for compressing the straws adjacent said loop for causing the ends of said straws to be 45 disposed radially with respect to said loop.

3. The process of making ornamental decorations consisting in arranging a plurality of elongated tubular translucent straws side by side, placing an elongated flexible element about the straws transversely and between the ends thereof; twisting the ends of said element together for providing a loop portion thereof encircling the straws, and further twisting the ends of said element for compressing portions of the straws within said loop and causing the ends of said straws to be radially disposed with respect to said loop. 55

FREDERICK W. OLTMANNS.
